UNITED STATES PATENT OFFICE

FREDERICK GUSTAVOUS GINZLER, OF LONDON, ENGLAND, ASSIGNOR OF ONE-HALF
TO HARRY CLIFFORD WALLIS, OF LONDON, ENGLAND

CLOSURE DEVICE

Application filed June 18, 1928, Serial No. 236,110, and in Great Britain January 24, 1928.

This invention relates to a closure device of the cap type and intended for closing a bottle, jar or the like container having a rim or external shoulder around its mouth.

5 The invention has for object to provide a closure which, after it has been affixed in position and removed therefrom, cannot be replaced without showing that it has been removed, and is inexpensive to manufacture 10 and reliable in use. Other objects of the invention are to provide a closure which consists of two parts connected together, viz. a metal embracing band and a lid of penetrable material such as cardboard, and also 15 to provide a quickly disconnectable means between said band and said lid. A further object is to provide a two-part closure which can be inturned or "wheeled" below the rim of the container mouth so as to secure the 20 capsule in position.

The invention is hereafter described with reference to the accompanying drawings: Figure 1 is a plan view of the closure ready to be affixed upon the container mouth and 25 Figure 2 is a side elevation thereof. Figure 3 is a view similar to Figure 2 showing the closure after the wheeling operation has been performed. Figure 4 is a plan view showing the metal embracing band partly 30 torn away from the penetrable disc. Figure 5 is a plan view of the metal embracing band removed from the disc. Figure 6 is a section on line 6-6 of Figure 5. Figure 7 is a plan view of a modification in which the ends of 35 the band overlap one another. Figure 8 is a plan of a further modification.

In these drawings a lid of penetrable material such as cardboard, cork or the like disc, is shown at *a*. This lid *a* is shown in 40 Figure 1 engaged by an embracing band of metal *b* having separated ends. The band *b* in this example is of such a length that its ends do not meet around the mouth of the 45 container *g* but face one another with a small gap *c* between. The band *b* is provided with a flange *d* at top and at bottom the band depends below the widest portion of the bead or rim *h* upon the container *g*. 50 This dependent portion is shown in Figure 2

as a skirt *b* and in Figure 3 such skirt is inturned below the bead *h*.

A tongue *e* provided upon the central portion of the band at one end of said band and not provided with the flange *d*, overlaps the gap *c* and the other end of the band *b*. The flange *d* overlaps the periphery of the lid *a* and it is provided with inwardly directed serrations or claws *f* which are downturned to bite into the periphery of the lid *a*. These claws *f* are preferably arranged in sets along or around the flange *d*, four such sets being shown in the drawings (Figures 1 and 4). Further, it is advantageous to locate one of said sets of claws *f* with one half the set near each of the adjacent ends of the flange *d* and close to the gap *c*. In other words, one of the four sets is divided on each side of gap *c*, as clearly seen in Figure 4.

If desired, a gasket *i* of the usual kind may be mounted on top of the container mouth, see Figure 2.

The metal band *b* and the lid *a* are secured together before the closure is mounted on the container mouth. The closure so formed with the serrations or claws *f* biting into the lid *a* is held down upon the mouth of the bottle or container with the band *b* embracing the rim or bead *h* upon the exterior of the container mouth, and the lower edge or skirt *b* of the band *b* is then wheeled or inturned below the external rim or bead *h*, which operation secures the closure in position. This wheeling operation is well known in connection with closure devices and it is thought unnecessary to describe it more fully.

By pulling the tongue *e* away from the disc *a*, the claws *f* upon that end of the band *b* will be torn from the material of the disc *a* (see Figure 4) and the metal band *b* will consequently, for a portion of its length, be disengaged from the rim *h*. This opening out of the embracing band *b* allows the closure to be removed from the mouth of the container. The lid *a* shows where the claws *f* have been torn out, so that it provides evidence of the closure having been removed.

It will be noted, first, that the disc or lid *a* holds the metal band *b* in the closed or

encircling position by means of the serrations *f*, secondly, that the wheeling of the lower edge of the band *b* holds that member in the known manner under the rim *h* of the container, and thirdly, that the material of the disc *a* yields and gives way when a pull takes place on the overlapping tongue *e* and it is desired to remove the closure.

By reason of the tearing of the claws *f* from the lid *a* and the consequent marks upon the periphery of the lid *a* near the tongue *e*, the closure will clearly show that it has been removed.

In Figure 7, the separated ends of the band *b* overlap one another by means of a step *j* in the length of the band, the tongue *e* being a continuation of the overlapping part of the band *b*.

Figure 8 shows another modification in which the claws *f* are provided upon wider portions or extensions *d'* of the flange *d*. These extensions *d'* are directed radially inwardly of the lid *a* or embracing band *b*, so as to enable the said claws to bite into the material of the lid *a* at points more distant from the extreme periphery of the lid than is the case in Figure 1, for instance. In this arrangement the tongue *e* enables the one end of the band to be further separated from the other and the claws on said first mentioned end to be torn from the material of the lid.

What I claim is:—

1. A closure device embodying therein a clamping band having separable ends, a lid of penetrable material, and means, holding said band in closed position about, and connecting it to, said lid, comprising projections upon said band penetrating the material of said lid.

2. A closure device embodying therein a clamping band having an inturned flange and separable ends, a lid of penetrable material, and means, holding said band in closed position about, and connecting it to, said lid, comprising projections upon the inturned flange of said band penetrating the material of said lid.

3. A closure device embodying therein a clamping band having separable ends, a lid of penetrable material, and means, holding said band in closed position about, and connecting it to, said lid, comprising a plurality of spaced claws upon said band penetrating the material of said lid.

4. A closure device embodying therein a clamping band having an inturned flange and separable ends, a lid of penetrable material, and means, holding said band in closed position about, and connecting it to, said lid, comprising a plurality of spaced claws upon the inturned flange of said band penetrating the material of said lid.

5. A closure device embodying therein a clamping band having separable ends, a lid

of penetrable material, means, holding said band in closed position about, and connecting it to, said lid, comprising projections upon said band penetrating the material of said lid, and means, facilitating the separation of the ends of said band, comprising a tongue carried by one end thereof and lapping the other end thereof.

6. A closure device embodying therein a clamping band having separable ends, a lid of penetrable material, and means, holding said band in closed position about, and connecting it to, said lid, comprising a plurality of sets of claws respectively adjacent each end of said band and at spaced intervals about the band, and penetrating the material of said lid.

7. A closure device embodying therein a clamping band having an inturned flange and separable ends, a lid of penetrable material, and means, holding said band in closed position about, and connecting it to, said lid, comprising a plurality of sets of claws upon the inturned flange of said band, said claws being positioned respectively adjacent each end of said band and at spaced intervals about the band, and penetrating the material of said lid.

8. A closure device embodying therein a clamping band having an inturned flange and separable ends, a lid of penetrable material, means, holding said band in closed position about, and connecting it to, said lid, comprising a plurality of sets of claws upon the inturned flange of said band, said claws being positioned respectively adjacent each end of said band and at spaced intervals about the band, and penetrating the material of said lid, and means, facilitating the separation of the ends of said band, comprising a tongue carried by one end thereof and lapping the other end thereof.

In testimony whereof I hereunto affix my signature.

FREDERICK GUSTAVOUS GINZLER.
